UNITED STATES PATENT OFFICE.

ARTHUR KATZINGER, OF CHICAGO, ILLINOIS, ASSIGNOR TO EDWARD KATZINGER COMPANY, OF CHICAGO, ILLINOIS.

REINFORCED DRAWN BAKING PAN.

Application filed September 2, 1926. Serial No. 133,257.

This invention relates to pans used for baking bread, cake and similar materials, used ordinarily by the wholesale bakeries, although obviously the same construction 5 can be used for domestic cooking purposes and for many other purposes some of which are mentioned herein.

The object of this invention is to provide a strong durable and simple sanitary baking pan and one which will give more satisfactory results than others now on the market.

This invention provides a maximum of strength and durability with a minimum of 15 expense. Other objects will be apparent from the description and drawings attached hereto.

Referring to the drawings Figure I shows a plan view of a series of three pans attached together in a unit in accordance with 20 my invention. Figure II shows a side elevation in section while Figure III shows an end elevation partly in section.

Referring to the drawings more specifically (1) represents a typical pan which is 25 preferably drawn from one piece. (2) indicates the bottom portion of the pan and (3) and (4) the side members. The side portions are connected to the bottom by radii 30 (5) and (6). Sides (3) and (4) are inclined from the vertical by an angle which is varied to suit the requirements but ordinarily averages about one quarter inch of flare on a depth of two and one half inches 35 to three inches.

The pans are held together by a band or strap (7) which is ordinarily formed of one piece for encircling the entire series of pans. The strap (7) is of a half round section and 40 disposed with its flat side against the pans.

The pans are formed with a flange extending horizontally at the top portion in the direction of the four sides. In the case of an end pan three of the flanges are folded over 45 the strap (7) as indicated by reference #8 on the drawings. The third or remaining flange is connected to the adjacent flange of the adjacent pan by the series of rivets (9). The flanges which are rolled over the half 50 round strap (7) may, if desired, be riveted or spot welded to this strap, but in many cases where a heavy gauge of metal is em-

ployed the stiffness of the metal appears to be sufficient to hold the strap into place. Spot welded or other types of fastenings 55 may be substituted for rivets (9) if desired.

In the case of intermediate pans, that is pans which do not form one of the end members of the series, the two flanges on the short 60 sides are rolled over the half round strap while both flanges on the long sides are fastened to adjacent flanges of adjacent pans as shown.

In addition to the rivets (9) a series of 65 holes or perforations (10) are shown. These perforations extend preferably through both of the flanges which are fastened together and serve to permit the circulation of air upward along the sides of the pan.

Referring to Figure III (11) indicates the flange on the pan which is sectioned while (12) indicates the flange on the adjacent pan which is placed beneath and riveted to flange (11) by rivet (13).

The pans are preferably made with a black finish on the outer side and a bright metallic finish on the interior side although this invention is not restricted to such an arrangement.

I am aware that pans have been fabricated into units by rolling flanges about a round wire. This invention does not cover the round wire, but represents a decided improvement in that the half round rod or 85 strap is much larger and much stiffer and by its shape supports the pans more satisfactorily than would the round wire. As far as I am aware the round wire type of reenforcing for connecting pans into groups 90 has been discarded long ago. In order to secure sufficient strength and rigidity from the round wire reenforcing strip the diameter of the wire which was required was so great that the pans were unduly bulky, 95 clumsy and heavy. Further the round wire left a large portion of the pan without proper support or reenforcement. A round wire would obviously be in contact with the side of the pan only along a single line.

On the other hand, the half round reenforcing which I have invented is in contact in the side of the pan over a distance as wide as its diameter and as long as the

2
side of the pan. This arrangement greatly reinforces the pans. Further the half round rod weighs only one half as much as a cylindrical rod of the size which would give satisfactory reinforcing. The round rod also permits of ready forming in such a manner as to entirely surround a group of pans.

The half round rod is, of course, much superior to a flat strip for many obvious 10 reasons.

It will be apparent that many modifications can be made in the details of construction here disclosed without departing from the spirit of this invention.

15 One of the essentials of this invention is the use of relatively heavy sheets in the formation of the pans. It will be obvious that if light gauge tin plate or other sheet is used for forming the pans the flange 20 which is curved over the half round rod will not have sufficient stiffness and strength to rigidly hold the set of pans in place. My invention depends, among other factors, upon the stiffness or strength of the curved 25 flange to hold the pans in a strong or rigid unit. As far as my knowledge goes this construction has never been used before and offers positive advantages in strength, simplicity, economy, freedom from catching 30 dirt or grease and ease of cleaning as well as durability.

Having now fully described my invention what I claim as new and wish to cover by

Letters Patent in the United States is as follows:

1. A series of drawn seamless baking pans, each formed from a single sheet of tin plate without seam or joint, and with large radii at each corner, said pans being formed into a set and arranged side by side, each 40 of said pans having a continuous integral flange on all four sides, a half round strap surrounding the series of pans, and arranged with the flat side adjacent the pans, each of the ends of the series of pans having flanges 45 on three of its sides drawn over said half round strap and each of the intermediate pans having flanges on two of its sides riveted together and perforated.

2. A series of drawn seamless baking 50 pans, each formed from a single sheet of tin plate, without seam or joint and with large radii at each corner, said pans being formed into a set and arranged side by side, each of said pans having a continuous integral 55 flange on all four sides, an elongated section strap surrounding the series of pans and arranged with the flat side adjacent the pans, each of the ends of the series of pans having flanges on three of its sides drawn over said elongated section strap, and each of the intermediate pans having flanges on 60 two of its sides riveted together and perforated.

ARTHUR KATZINGER.
